UNITED STATES PATENT OFFICE.

CHARLES C. HUFFMAN, OF CHICAGO, ILLINOIS, ASSIGNOR TO SUNBEAM CHEMICAL COMPANY, OF CHICAGO, ILLINOIS, A CORPORATION OF ILLINOIS.

UNIVERSAL BROWN DYE AND METHOD OF PRODUCING THE SAME.

1,274,048.

Specification of Letters Patent. Patented July 30, 1918.

No Drawing

Application filed September 24, 1917. Serial No. 192,873.

To all whom it may concern:

Be it known that I, CHARLES C. HUFFMAN, a citizen of the United States, and resident of Chicago, in the county of Cook and State of Illinois, have discovered a certain new and useful Universal Brown Dye and Methods of Producing the Same, of which the following is a specification.

My discovery relates to dyes and particularly to a novel brown dye soap having peculiar and advantageous qualities.

I am aware that heretofore dyes have been incorporated in soaps with the object in view of providing a simple carrier for the dye and fairly satisfactory results may be secured if certain neutral dyes are employed and if the water in which the substance is used is of exactly the right temperature.

One of the most important features of my novel discovery is that the shade of color which is secured in the use of the article is the same whether a large or small quantity is employed and whether it is used in hot or cold water. It is preferably used with hot water for the reason that the soap will not act to thoroughly cleanse the article unless the water is hot. The effect of deepening the shades by the use of hot water is not present and this is of great importance if it be desired to reproduce certain colors. The ordinary user has no means of determining whether the same temperature is employed in each instance. Neither would he be able to determine whether exactly the same quantity of the dyeing material was employed. By the use of my product the colors may be duplicated with ease and certainty.

My improved dye soap should not be confused with those in which the soap acts merely as a carrier or vehicle for the dye, as the following description will show that the final product is the result of peculiar reactions which take place between the dye and the elements of the soap and which product could not be secured by the use of the materials heretofore employed or as heretofore combined. By reason of the novel process of compounding and the selection of substances which enter into the compound, a dye is produced which is equal if not superior to those which require boiling and the addition of a mordant for setting the color.

An important distinction of my dye soap over any such article heretofore produced is that the soap is manufactured by the cold

process and many advantages result therefrom.

A further important distinction of the dyes produced by me is that they are alkali proof, irrespective of the characteristics of the dyes, that is, basic, neutral or acid, before combining in the soap.

A still further distinction is that the dyes are universal, that is, adaptable to either cotton, wool, silk or flax, or mixtures thereof.

One of the important advantages following the use of the method disclosed is that of allowing the glycerol, which is a by-product of the saponification process, to remain in the product. This is liberated when the soap is dissolved and cooperates with the dye in attacking the fabric. Furthermore, it assists in fixing the colors following the application of heat, as in the act of ironing, after the fabric has been dried.

The dye herein considered is composed of a number of different colors and the method of combining them without precipitation forms an important feature of this invention.

The composition and the method of preparing it will now be described in detail.

In order to establish a basis for the proportions of ingredients, it will be assumed that it is desired to produce five gross of one ounce bars of the soap. To produce this quantity, three gallons and forty-two ounces of vegetable oil and one gallon and twenty-four ounces of sodium hydroxide (NaOH) of a specific gravity of 1.40 at 65° F. are combined. The oil or oils used may be varied. Olive, soy bean, raisin, peanut, crude corn, or any vegetable oil may be used separately or combined with cocoanut oil. The proportions of the cocoanut oil and other oils will vary according to weather conditions. Under normal conditions one gallon, fourteen ounces of cocoanut oil will be employed to two gallons, twenty-eight ounces of the other oils. In warm, dry weather the proportion of cocoanut oil should be lessened and increased in cool, damp weather.

The oil and caustic soda are mixed until saponification is nearly completed at which time the first of the dye solutions is added.

In producing brown I employ an anilin acid red, a chrysoidin yellow, a direct black and a methylene blue. These four colors are separately dissolved, each in one quart of boiling water and added to the incom-

pletely saponified soap compound in the order mentioned. Between additions a sufficient time is allowed for substantially complete reaction and thorough mixing. The 5 addition of the hot water together with the heat of reaction of the dyes, with the excess of sodium hydroxid, serves to produce a dye having a complex formula which has not been determined but which has the 10 characteristic of being universal and alkali proof. The important point is that dyes having different degrees of acidity and alkalinity are combined without precipitation. In ordinary practice it is known that 15 chrysoidin will precipitate the red and the red will precipitate the methylene blue if mixed in an aqueous solution. The final dye produced is not a mere mechanical mixture of the primary colors but is a new, 20 permanent, alkali proof dye. Neither is it a mere mechanical mixture with the soap compound. The soap acts as a reagent and assists in the formation of the new compound.

25 After allowing a few minutes for the reaction to take place and after the dye has become thoroughly mixed with the soap, the soap is poured into molds where it is allowed to remain at a temperature of about 30 80° F. for forty-eight hours.

By comparison of the proportions of vegetable oil and sodium hydroxid it will be noticed that there is a substantial excess of the latter even when the water containing the dye is added. Of course, the amount of the saponifying agent may be varied somewhat but in any case an excess should be employed.

It will be noted that the glycerol is not 40 removed from the product and therefore will be released as the soap is dissolved. It will be absorbed by the fabric along with the dye and will assist in fixing the dye when heat is applied to the fabric as in ironing. It has furthermore, an advantageous 45 effect on the fabric in softening the same and brightening the colors.

In use the soap and the garment or fabric to be dyed are introduced into hot water 50 and the soap is applied directly to the fabric to thoroughly cleanse the same. Even though the soap is applied locally or only in spots the coloring will be even. Furthermore, the hands or container will not be 55 colored. After the article is cleansed and dyed it is rinsed in cold water and dried in the usual manner. The dye will be found to be alkali proof.

Different shades of brown from a copper 60 to a chocolate color may be secured by variations in the proportions employed. To produce a medium brown for the quantity of soap specified I employ substantially seven and one-half ounces avoirdupois of 65 red, seven and one-half ounces of yellow,

five ounces of black and half an ounce of blue.

Attention is also called to the fact that the soap is manufactured by the cold process. By reason of this process of manufacture I am enabled to secure an absolutely uniform product with regard to the colors produced. The low temperatures employed are much more easily controlled and the necessary reaction between the soap and the 70 dye is completed with a certainty which is not possible in a settled soap.

While reference is made herein to the use of sodium hydroxid as the saponifying agent, other chemicals having a similar action may be used if desired. For instance, potassium hydroxid has been found to operate satisfactorily. Of course, the quantity of the saponifying agent required will vary somewhat in accordance with the strength or 75 specific gravity thereof.

4 claim:

1. The method of producing a mixed dye soap which consists in preparing a solution of vegetable oil and an excess of a saponifying 80 agent, then singly adding thereto just prior to complete saponification such anilin dyes as are necessary for producing the desired color and allowing the reaction following the addition of each color to be substantially complete before the addition of another color, substantially as described.

2. A universal brown dye soap composed 90 of the reaction products of substantially four hundred and twenty-six fluid ounces of a 100 vegetable oil, substantially one hundred and fifty-two fluid ounces of sodium hydroxid of a specific gravity of 1.40 at 65° F., substantially seven and one-half ounces avoirdupois of anilin acid red, substantially seven 105 and one-half ounces of chrysoidin yellow, substantially five ounces direct black, and substantially one-half ounce of methylene blue, combined as specified.

3. A universal brown dye soap composed 110 of the reaction products of substantially four hundred and twenty-six fluid ounces of a vegetable oil, substantially one hundred and fifty-two fluid ounces of sodium hydroxid of a specific gravity of 1.40 at 65° F., substantially 115 seven and one-half ounces avoirdupois of anilin acid red, substantially seven and one-half ounces of chrysoidin yellow, substantially five ounces direct black, and substantially one-half ounce of methylene blue, 120 the colors being singly dissolved in substantially thirty-two fluid ounces of hot water and added singly to the soap compound before saponification is complete.

4. The herein described dye soap composed 125 of the reaction products of a vegetable oil, a saponifying agent, and a plurality of anilin dyes having materially different degrees of acidity and alkalinity, substantially as described.

5. The herein described substance for simultaneously cleansing and dyeing fabrics, composed of the reaction products of a saponifiable substance, a saponifying agent 5 in excess of that required to saponify the same, and a plurality of anilin dyes separately dissolved and singly added to the mass before saponification is complete, such time being allowed between successive additions as to avoid precipitation, substantially as described.
6. The new dye soap composed of the reaction products of a vegetable oil, a quantity

of a saponifying agent in excess of the theoretical quantity required to saponify the oil, 15 and a plurality of anilin dyes of different degrees of acidity or alkalinity, the dyes being separately dissolved and singly added to the mass before the oil is completely saponified.

Signed at Chicago, Ill., this 22nd day of September, 1917.

CHARLES C. HUFFMAN.

Witness:

T. D. BUTLER.
